(57) **CLAIM**

The ornamental design for a bed lift, as shown and described.

DESCRIPTION

FIG. 1 is a perspective view of the bed lift showing my new design;

FIG. 2 is a perspective view of the bed lift showing my new design, rotated 180 degrees from the view of FIG. 1;

FIG. 3 is a side view of the design of FIG. 1;

FIG. 4 is a side view of the design of FIG. 1, rotated 180 degrees from the view of FIG. 3, with sides adjacent to the side shown in FIG. 4 of the design being identical to that of FIG. 4;

FIG. 5 is a top view of the design of FIG. 1; and,
FIG. 6 is a bottom view of the design of FIG. 1.

The broken lines in the drawing depict environmental subject matter only and form no part of the claimed design.
